UNITED STATES PATENT OFFICE.

FREDERICK COCKER, OF DANBURY, CONNECTICUT, ASSIGNOR TO THE
HAT CURLING MACHINE COMPANY, OF SAME PLACE.

HAT-BRIM-CURLING MACHINE.

SPECIFICATION forming part of Letters Patent No. 286,908, dated October 16, 1883.

Application filed August 16, 1883. (No model.)

To all whom it may concern:

Be it known that I, FREDERICK COCKER, a subject of the Queen of Great Britain, and residing at Danbury, in the county of Fairfield 5 and State of Connecticut, have invented a certain new and useful Improvement in Hat-Brim-Curling Machines, of which the following is a specification.

My invention relates to that class of apparatus in which the outer edge of the hat-brim, in a moist state, is subjected to the action of one or more heated irons acting upon one side of the edge or rim, in conjunction with suitable "heels" or irons which act upon the other 15 side of the edge or rim. In this class of apparatus the hat-body is usually mounted upon a revolving bed or table, which presents the edge of the hat-brim continuously to the curling mechanism, and, therefore, for convenience, I have shown my invention as applied to a well-known and ordinary form of apparatus constructed upon said plan; but the principle may be adapted and applied to other forms of hat-brim-curling apparatus. Heretofore in organized machines of this class the actual ironing or compression of the "curl" or lap has been effected between the lower side of the heated iron and the upper surface of the hat-supporting table or bed, and the 25 "heel" or "opening-iron," as its name implies, has simply performed the function of reopening or raising the fold or curl after it has been pressed down flat upon the horizontal portion of the brim, for the purpose of imparting to it the requisite angle with relation to the latter. This construction and mode of 30 operation are suitable only for the formation of brims or "curls" which are angular in cross-section.

The object of my invention is to form curvilinear or "round" curls in cross-section by mechanical means and with an organized machine, and which curls are formed between irons acting upon the edge of the brim and not 35 between an iron and a surface, such as a revolving or stationary bed-plate or the like.

My invention consists in the special construction and arrangement of the curling-irons, which consist of a heating-iron the 40 ironing-surface of which is constructed in the form of a semicircular or other curvilinear

concave matrix, and of a correspondingly-formed convex heel or forming-iron, which forces the rim into and sustains it against the action of the opposed matrix, the formation, 55 ironing, and stiffening of the rim or curl being effected exclusively by and between the said parts.

In the accompanying drawings, which illustrate the application of my invention to one of the ordinary forms of hat-brim-curling machines, Figures 1 and 2 are respectively a side elevation and a plan of the main parts of the apparatus. Fig. 3 is a top view, and Fig. 4 a side elevation, of the convex heel or former. 65 Fig. 5 is a view of the under side of the heating-matrix and the convex former, the parts being shown as in positions which they assume with relation to each other during the operation of curling. Fig. 6 is a side elevation of 70 the matrix-iron, and Fig. 7 a vertical section through both the matrix-iron and the former in their relative positions during operation, showing a cross-section of a hat-brim under treatment.

In the drawings, A represents the frame of the machine, upon which is mounted centrally a revolving hat plate or support, B, which is actuated through the medium of suitable gearing, b, by the driving-shaft of the machine. The revolving hat-plate B is provided with an expansible brow-block, C, by which the hat-body is secured in the required position.

The curling devices D D, situated upon opposite sides of the revolving hat-plate, are mounted upon slides d d d' d', which are reciprocated by cam-surfaces c c' upon the revolving hat-support B in the usual manner, the cam-surfaces corresponding to and causing 85 the curling-tools to follow the shape of the hat-brim.

In general construction the matrix-irons M are substantially the same as those heretofore used, being made hollow, and provided with 90 openings to facilitate their being heated by a gas-jet in the usual way. They are secured to slides m m, which are in turn mounted upon the slides d' d', actuated directly by the tappet c of the revolving hat-plate B. The heel-pieces 95 or formers N are also mounted independently upon the slides d d', their outer or back ends

being pivoted thereto in such manner that their inner or working ends may be lowered to or raised from the revolving hat-plate B, as shown on opposite sides in Figs. 1 and 2. 5 The matrix-irons M may also be correspondingly advanced or retracted horizontally by means of eccentrics $m' m'$, for the purpose of bringing them into position to operate upon the hat-brim or to allow the hat to be removed. 10 The matrix m^2 , or portion of the heating-iron M which acts directly upon the hat-brim, is formed in the lower front edge of the iron in a longitudinal concave curve the radius of which is at least as great as that of the large 15 curves formed at the sides of the hat and constituting the edges of the side brims. This matrix m^2 is preferably semicircular in cross-section, although any other curvilinear form may be given to it, according to the style or 20 variety of curl to be imparted to the hat-brim. The matrix-groove m^2 is also formed, at one or both extremities, with an enlarged semi-trumpet-shaped mouth or guiding-surface, m^3 , so shaped as to take up and turn the edge of 25 the hat-brim as it advances, and gradually bend it into the narrowest part of the groove m^2 , where the ironing and compressing are accomplished. This action of turning and guiding the edge of the brim into the matrix-groove 30 m^2 is contributed to largely and insured by the breaking or forming iron N, which is in the shape of a convex curve the radius of which is at least no greater than that of the smaller or front and rear curves of the hat, 35 and is of semicircular or other convex curvilinear form in cross-section to correspond with the matrix m^2 , with the inner concave surface of which its outer convex surface is concentric in cross-section when the two irons are 40 brought into their proper relative positions for operation upon the edge of the hat-brim, as will be seen by reference to Fig. 7.

It will be observed that owing to the difference in the radii of the curve of the matrix 45 m^2 and the former N, the extremities of the latter diverge from the central portion of the matrix, as shown in Fig. 5, so that the edge of the hat-brim can readily enter between the two irons, and will be gradually and uniformly 50 guided by the convex surface of the former N into the matrix m^2 , and finally be compressed against its concave surface as the center is approached.

The operation is as follows: The expandible 55 brow-block B is contracted, and the hat-body placed in position upon the revolving hat-plate, and secured thereto by the re-expansion of the brow-block. The hat-plate is usually

set so as to present the front and rear portions of the hat-brim, at which points there 60 is little or no curl to be turned to the curling-irons. The heel or forming-iron N is then lowered, so that it rests upon the horizontal portion of the hat-brim, and the heating-iron M is then forced forward into position by means of the eccentric m' bringing the former N and matrix M into the relative positions shown in Figs. 5 and 7. The hat-plate B is then caused to revolve, gradually bringing the side brims of the hat under the action 65 of the curling-irons, which are made to advance toward or recede from the center, to conform to the shape of the hat, by means of the cams $c c'$ acting upon the slides $d d'$. As the edge of the side rim advances, it is received by the 70 enlarged entrance or mouth m^3 , which gradually raises its edge and guides it into and between the matrix m^2 and the former N, which latter, by its convergence toward the center, 75 forces the brim uniformly and evenly into the matrix, and sustains the inner side of the curl thus formed during its subjection to the heat and pressure. The change in the shape of the material thus being effected gradually and evenly, and both sides of the curl being rigidly sustained while subjected to the maximum degree of pressure, all danger of injury or derangement is avoided, and a stiffer and more permanent curl is produced than heretofore. 80

What I claim as my invention, and desire to secure by Letters Patent, is—

1. In an organized machine for curling hat-brims, an iron and a former adapted for making curvilinear curls, and which are capable 95 of making the curl independently of the hat-plate or other opposing surface, substantially as herein described.

2. The process of curling hat-brims in an organized machine, which consists of passing 100 the brim between curling-tools so shaped that the surfaces of the curling-tools alone act upon the hat-brim to compress and curl it, substantially as herein described.

3. The process of curling the brims of hats 105 in an organized machine, and in which the hat or the curling-tools are rotated, and which consists in bringing the edge of the brim gradually to the shape desired without folding the curl flat upon the brim, and then reopening 110 the said curl to arrive at the shape desired, substantially as herein described.

FREDERICK COCKER.
